UNITED STATES PATENT OFFICE.

FREDERIC A. CHANDLER, OF BOSTON, MASSACHUSETTS.

DESIGN FOR A SCHOOL-CHAIR.

SPECIFICATION forming part of Design No. 24,285, dated May 7, 1895.

Application filed February 28, 1895. Serial No. 540,108. Term of patent 7 years.

To all whom it may concern:

Be it known that I, FREDERIC A. CHANDLER, a citizen of the United States, residing at Boston, in the county of Suffolk and State of Massachusetts, have invented and produced a new and original Design for School-Chairs; and I do declare the following to be a full, clear, and exact description of the same, reference being had to the accompanying drawings, forming a part thereof.

Figure 1 is a perspective view of a chair embodying my design. Fig. 2 is a top plan view. Fig. 3 is a side view.

Similar letters refer to similar parts wherever they occur in the different figures of drawings.

The leading feature of my design consists in the back having a convex center piece the convex side of which is disposed toward the front of the chair and having its sides curved in such manner as to form an enlarged oval-shaped portion D, said center piece being situated between two rearwardly inclined uprights capped at their upper ends with a hori-

zontal straight top piece, as shown in the 25 drawings.

Referring to the drawings the letter A indicates the seat; B, B, the rearwardly inclined uprights, and C the horizontal straight top piece. The letter D indicates the ornamental center piece, which when viewed from the side has a contour extending in a gracefully curved line forwardly beyond the plane of the inclined uprights B, B, and when viewed from the front presents the curved ornamental configuration having as the distinguishing feature the enlarged central oval-shaped panel arranged approximately midway between the ends of said bent piece.

What I claim is—

The design for a chair as herein shown and described.

In testimony whereof I have affixed my signature in presence of two witnesses.

FREDERIC A. CHANDLER.
